BOMB OR SIMILAR DEVICE

George Zint, Wapakoneta, Ohio

Application October 21, 1941, Serial No. 415,962

5 Claims. (Cl. 102—2)

The invention relates primarily to bombs to be dropped from aircraft, and the present disclosure of the invention is of the parachute type.

The principal object of the invention is to provide a novel firing mechanism which will delay firing of the explosive charge sufficiently to allow the bomb to reach the earth from a predetermined altitude and will then effect explosion of said charge, and the same mechanism will operate to delay firing of the bomb for a desired time after it has landed, if said bomb be released from the aircraft at a lower altitude.

Another object is to provide a novel construction which is rather simple and inexpensive, yet efficient and reliable.

With the foregoing in view, the invention resides in the novel subject matter hereinafter described and claimed, description being accomplished by reference to the accompanying drawings.

Figure 1 is a side elevation showing the bomb immediately after leaving the aircraft.

Fig. 2 is a side elevation illustrating the parachute opened to control the descent.

Fig. 3 is a vertical sectional view partly in elevation showing the normal set relation of the various elements.

Fig. 4 is a fragmentary horizontal section on line 4—4 of Fig. 3.

Fig. 5 is an enlarged fragmentary section similar to Fig. 1 but illustrating the firing mechanism about to fire the detonator.

While only one form of the invention has been illustrated in the drawings and will be rather specifically described, it is to be understood that variations may be made within the scope of the invention as claimed. Moreover, it is possible to make use of the novel firing mechanism in bombs and the like other than those of aerial nature.

An explosive-carrying structure is shown in the form of a casing 6 divided by a horizontal partition 7, the space below said partition being utilized to carry the explosive 8, while the space above said partition accommodates firing mechanism as will be hereinafter described.

A base 9 is suitably secured upon the partition 7 and is provided at one end with an upstanding casing 10. A lug 11 projects upwardly from the other end of the base 9 and is provided with a recess 12 which opens away from said casing, said recess containing a detonator 13. An opening 14 is formed in the lug 11 and extends from the recess 12 through the side of said lug toward the casing 10. The detonator 13

is secured in place in the recess 12 by means of a screw cap 15, and this cap also secures one end of a fuse 16 in contact with said detonator. The other end of the fuse 16 extends to an opening 17 in the partition 7 and is suitably coupled to said partition as denoted at 18. Thus, when the detonator 13 is fired, it ignites the fuse 16 and this fuse ignites the explosive charge 8.

An angular arm 18 is secured to and projects upwardly from the base 9 between the casing 10 and the lug 11. This arm is formed with a lower opening 19 alined with the opening 14 of the lug 11, and said arm is also formed with an upper opening 19' for a purpose to appear. The side of the casing 10 toward the arm 18 is provided with an opening 20 alined with the openings 14 and 19, and the opposite side of said casing is formed with another opening 21. A firing pin 22 for the detonator 13 extends slidably through the openings 14, 19 and 20, said firing pin being provided with an operating spring 23 which acts against the collar 24 on said pin and reacts against a portion of the arm 18. A link 25 preferably formed from a tubular piece of zinc is connected with the inner end of the firing pin 22, passes through the opening 21, and is held against inward movement by means of a pin 26. Thus, this link 25 holds the firing pin 22 normally against operation. The outer end of the link 25 is preferably enclosed in a cap 27 threaded upon a boss 28 on the casing 10. The opposite side of this casing is preferably provided with a tapered boss 29 normally engaged by a cap 30 on the firing pin to prevent leakage of any of the acid hereinafter described.

The interior of the casing 10 includes an upper chamber 31 and a lower chamber 32, and said casing is provided with an internal ledge 33 between said chambers. Resting upon this ledge 33 is a frangible container 34 preferably formed from glass, said container holding a quantity of acid 34' (preferably muriatic) to eat the link 25 when said container is broken, thereby releasing the firing pin 22 so that it may fire the detonator 13. A striker rod 35 is employed to break the container 34 at the proper time, one end of this rod being slidably in the above described opening 19' of the arm 18 while the other end of said rod is similarly received in an opening 36 in the casing 10. An actuating spring 37 is provided for the rod 35 but this rod is normally held against operation by means of a spring-held latch 38 engaging a notch 39 in said rod as seen in Fig. 3. For guiding the latch 38, I have shown a lug 40 on the upper end of arm 18. When this

latch is released, the spring 37 forces the striker rod 35 inwardly as seen in Fig. 5 thereby shattering the container 34 and spilling the acid 34' into the lower chamber 32, where it eats away the link 25 to release the firing pin 22.

To prevent any leakage of acid through the opening 36, the casing 10 is by preference provided with a tapered nipple 41 tightly engaged by a cap 41' on the striker rod 35 when this rod is moved to its operative position.

Slidably vertically in the upper portion of the chamber 31 is a plunger 42 which rests normally upon the container 34, and if this container be provided with a cork or the like 43, the plunger will hold said cork in place. A compression spring 44 acts downwardly upon the plunger 42 and reacts against a cap 45 which closes the upper end of the casing. The spring-pressed plunger thus not only holds the acid container 34 tightly in place but when said container is shattered by the striker pin 35, said plunger will force the fragments of glass and the acid 34' downwardly, the acid entering the lower chamber 32 and immediately starting to eat the link 25.

Connected with the latch 38 is a cable or the like 46 which passes through an opening 46' in the top of the casing 6, said cable being connected to the shroud lines 47 of a parachute 48. As the entire device is released from an aircraft, an eye 49 at the top of the parachute, is the last part to be released, with the result that sufficient jerk is given upon the cable 47 to release the latch 38. Thus, the striker pin 35 immediately acts to shatter the acid container 34, the acid enters the lower chamber 32 of the casing 10 and starts to eat the link 25. When this link is eaten substantially in two, the spring 23 comes into play to break the remaining portion of the link and operate the firing pin 22. This firing pin fires the detonator 13 which in turn fires the fuse 16, and the latter fires the charge 8. It is, of course, known how long it will take the acid to effect release of the firing pin 22. It is thus known how much time must be allowed for the bomb to reach the earth before exploding, and by releasing said bomb at the proper altitude, it may be made to explode substantially upon striking the earth, or a short time before or after striking, as most advantageous.

I claim:

1. In a bomb or similar device having a detonator and a spring-actuated firing pin for said detonator, a link aligned with said firing pin, said link being anchored at one end and having its other end directly connected to said firing pin to hold the latter against operation, a chamber containing at least a portion of said link, an acid for eating said link to release said firing pin, a frangible container containing said acid and mounted in position to spill said acid into said chamber when broken, and means for breaking said frangible container.

2. In a bomb or similar device, an explosive-carrying structure, a detonator carried by said structure, a casing secured to said structure and having two openings from its interior to its exterior, a spring-actuated firing pin passing slidably through one of said openings and positioned in operative relation with said detonator, a link connected with said firing pin and

normally holding the same against operation, said link having at least a portion within said casing, a quantity of acid to eat said link and release said firing pin, a frangible container in said casing and containing said acid, said frangible container having a portion opposite the other of said openings, a spring-actuated striker having an inner end received in said other of said openings to strike and break said frangible container, and a latch normally engaged with said striker and holding the same against operation.

3. In a bomb or similar device, an explosive-carrying structure, a detonator carried by said structure, a casing secured to said structure and having upper and lower communicating chambers, said casing having an upper opening from its exterior to said upper chamber and a lower opening from its exterior to said lower chamber, said casing being also provided with an internal ledge between said chambers, a spring-actuated firing pin extending slidably through said lower opening and operatively positioned with respect to said detonator, a link connected with said firing pin and normally holding the same against operation, said link having at least a portion in said lower chamber, a quantity of acid to eat said link and release said firing pin, a frangible container in said upper chamber resting upon said ledge and containing said acid, a spring-actuated striker having an inner end received in said upper opening to strike and break said frangible container, and a latch normally holding said striker against operation.

4. A structure as specified in claim 3; together with a plunger in said upper chamber resting upon said frangible container, and a spring acting downwardly upon said plunger to force the acid into said lower chamber when said container is broken.

5. In a bomb or similar device, a base, a casing secured to and projecting upwardly from one end of said base, a lug projecting upwardly from the other end of said base, said lug having a detonator-receiving recess which opens away from said casing and an opening extending from said recess through the side of said lug toward said casing, a detonator in said recess and a fuse contacting with said detonator, means securing said detonator and fuse in place, an arm secured to and projecting upwardly from said base between said lug and said casing, said arm and casing having openings aligned with said opening of said lug, a spring-actuated firing pin slidably in these three openings for firing said detonator, a link connected with said firing pin and normally holding it against operation, said link having at least a portion in the lower end of said casing, a quantity of acid to eat said link and release said firing pin, a frangible container mounted in the upper portion of said casing and containing said acid, a spring-actuated striker rod for breaking said container, said casing and arm having openings in which said striker rod is slidably mounted, a latch mounted on said arm and normally engaging said striker rod to hold same against operation, and a releasing element connected with and extending from said latch.
